COMBINED CAN OPENER AND SPOUT

Charles G. Campbell, Miamisburg, Ohio, assignor to The Huffman Manufacturing Company, Miamisburg, Ohio, a corporation of Ohio

Filed Aug. 8, 1969, Ser. No. 18,592

Term of patent 14 years

Int. Cl. D9—99

U.S. Cl. D9—290

FIG. 1 is a perspective view of a combined can opener and spout showing my new design;

FIG. 2 is a view of one side thereof;

FIG. 3 is a view of the opposite side thereof;

FIG. 4 is a front view thereof;

FIG. 5 is a rear view thereof;

FIG. 6 is a top view thereof; and

FIG. 7 is a bottom view thereof.

I claim:

The ornamental design for a combined can opener and spout, substantially as shown.
